INTERNAL COMBUSTION ENGINE

Edward Francis Arblaster, Mount Lawley,
Western Australia, Australia

Application January 21, 1933, Serial No. 652,902

3 Claims. (Cl. 123—80)

This invention relates to improvements in internal combustion engines. The improvements particularly concern the valve mechanism which is of the sleeve valve type. Existing sleeve valve mechanism has several disadvantages among which the most serious is that it is not possible to obtain really rapid acceleration.

5

The present mechanism is so arranged that full and very rapid exhaust port openings is obtained, a factor which, together with a free intake, enables rapid acceleration.

The invention consists broadly in the use of a rotary reciprocating sleeve having a plurality of openings adapted to register at correct intervals with the exhaust and intake openings in the cylinder, driving means being arranged so as to obtain maximum exhaust opening. To achieve the foregoing, the characteristic feature is that the sleeve is connected to or has formed 20 integrally therewith a spur wheel having comparatively long teeth oblique to the axis of the sleeve.

The foregoing and other features of the invention will readily be understood by reference 25 to the accompanying drawing in which—

Fig. 1 is an elevation partly sectional showing the cylinder and driving means for the sleeve. In this view the various exhaust and intake passages and water jacket (if used) have been omitted for the sake of clearness.

Fig. 2 is a side elevation mainly sectional of a cylinder and its associated rotary reciprocating sleeve whilst

Fig. 3 is a sectional plan showing half of two adjacent cylinders taken through the line of the exhaust passages. This view is merely to illustrate how the passages can be arranged.

As shown in the drawing there is a cylinder 10 which, towards its upper end, has a plurality 40 of exhaust and inlet ports equally formed around its circumference. The four exhaust ports are referenced 11 and the four intake ports are referenced 12. It will be understood that these ports are permanently in direct communication 45 with corresponding exhaust and inlet passages. Placed inside the cylinder 10 and adapted to move therein to a regulated extent is a reciprocating and rotary sleeve 13. It is inside this sleeve that the piston (not shown) reciprocates 50 in the normal manner. The sleeve 13, near its end, is provided with a plurality (four) uniformly spaced valve openings 14. These valve openings 14, when they are in alignment with ports in the cylinder 10, are alternately all functioning 55 as exhaust valve openings or all as intake valve

openings. Towards the other end the sleeve 13 has connected or formed integrally on the outer periphery thereof a spur wheel 15 having comparatively long teeth which are oblique to the axis of the sleeve. The sleeve will also be 60 provided with a spiral groove 16 for lubricating purposes. A further extension of the sleeve 13 is in the form of two parallel circumferential collars 17 and 18, the space between which is in the form of a circumferential channel. Embracing 65 or engaging the sleeve 13, either completely or partly around the groove formed between the collars 17 and 18, is a thrust collar 19 which may, if desired, have friction reducing bearings interposed. This thrust collar 19 extends to or is 70 rigidly connected to a cross head 20. This cross head is fulcrumed to a short link or connecting rod 21 that engages a crank pin 22 and is so reciprocated from a cam shaft. A worm 23 engages and drives the spur teeth 15 and is itself supported on the cam shaft 24 that corresponds to the ordinary cam shaft and is driven in the same ratio, namely two to one.

The piston rod is referenced 25, the exhaust 80 passages 26 and the inlet passages 27.

There is a sealing ring 28 forming part of an extension of the head projecting down into the cylinder so as to seal the valve openings 14 when they are above the level of the ports 11 and 12.

The arrangement described operates as follows:—

In the first place the piston, inside the sleeve 13, reciprocates in the normal manner. The sleeve itself is under two influences:—It is continuously reciprocated by reason of its engagement by the thrust collar 19 driven through the cross head 20. In addition, however, the sleeve 13 is rotated. This is effected directly by the driving influence of the worm 23 and indirectly 90 by the obliquity of the teeth 15. The rotation, or rotating influence, by means of the worm 23, naturally tends to be uniform. This uniform tendency to rotation is, however, either increased or decreased by the obliquity of the teeth 15. 95 When the sleeve 13 is pulled down the effect is that the worm 23 is caused to partly function as a cam. In other words, if the worm was stationary when the sleeve 13 was pulled down such sleeve would be given a turning effect to an extent 100 equal to the obliquity of the teeth 15 for the distance that the downward pull was exerted. Whilst the worm 23 is functioning as a cam when the sleeve 13 is pulled downward, at the same 105 time it is turning and so also functioning normal- 110

ly to turn the sleeve 13. In consequence, when the sleeve 13 is being pulled downwardly the turning effect thereon is approximately doubled. On the other hand, when the sleeve 13 is pushed upwardly the effect is to tend to turn the sleeve in the opposite direction by reason of the obliquity of the teeth 15 and the cam effect on the worm 23, although this is neutralized by the turning effect of the worm.

10 The actual effect is, therefore, that when the sleeve is going upwardly there is practically no turning effect on the sleeve. The effect of the foregoing is that when the exhaust stroke is about to commence the valve openings 14 are 15 above the exhaust ports 11 (see upper dotted outline in Fig. 1). As the stroke proceeds the sleeve is pulled down and simultaneously given a comparatively rapid turning movement so that the whole four exhaust ports are uncovered rapidly.

20 When the exhaust stroke is completed the valve openings 14 are in the position shown in the lower dotted outline in Fig. 1. The next movement of the sleeve 13 is an upward movement and it corresponds to the intake. This upward movement is, however, not accompanied by any appreciable turning effect as previously explained so that a valve 14 is in the position shown as dot dash outline in Fig. 1 at the end of the stroke. The relative shape of the intake ports 12 and 30 valve openings 14 insures that adequate intake opening is provided. During the next two strokes, that is to say, during compression and explosion, the sleeve 13 operates in a similar manner to that previously explained except that now 35 it is at a level above the ports 11 and 12 and actually the valve openings are sealed by the ring 28.

It should be noted that eight complete revolutions of the engine result in one complete revolution of the sleeve 13.

In practice the sleeves 13 of a plurality of cylinders 10 will be arranged so as to be driven by the one shaft 24 and a number of worms 23 and links 21.

45

It is to be understood that the means employed to drive the spur wheel having oblique teeth 15, attached or integral with the sleeve 13, are capable of variation. Thus, it can be driven by means of a vertical pinion fashioned, of course, to correctly 80 mesh with the teeth. In this case the only alteration involved will be difference in the driving means although the normal ratio should be preserved.

I claim:—

1. In internal combustion engines a rotary and reciprocating valve sleeve having comparatively long teeth oblique to the axis of said sleeve, co-acting with a toothed member and additional means operatively connecting the valve sleeve 90 with the said toothed member in such a manner that the rotation of the sleeve is increased when the sleeve is reciprocated in one direction and that the said rotation is retarded when the sleeve is reciprocated in the opposite direction, for the purpose described.

2. In internal combustion engines a rotary and reciprocating valve sleeve having comparatively long teeth oblique to the axis of said sleeve, co-acting with a rotary worm and additional means 100 operatively connecting the valve sleeve with the said rotary worm in such a manner that the rotation of the sleeve is increased when the sleeve is reciprocated in one direction and that the said rotation is retarded when the sleeve is reciprocated in the opposite direction, for the purpose described.

3. In internal combustion engines a rotary and reciprocating valve sleeve having comparatively long teeth oblique to the axis of said sleeve, co-acting with a toothed member and a link connected to the valve sleeve and eccentrically connected to the said toothed member in such a manner that the rotation of the sleeve is increased when the sleeve is reciprocated in one direction 110 and that the said rotation is retarded when the sleeve is reciprocated in the opposite direction, for the purpose described.

EDWARD FRANCIS ARBLASTER.
